UNITED STATES PATENT OFFICE.

ARTHUR S. NEWSHAM AND PAUL A. VIERSEN, OF CHICAGO, ILLINOIS, AND GUSTAV MISCH, OF PITTSBURGH, PENNSYLVANIA, ASSIGNEES, BY DIRECT AND MESNE ASSIGNMENTS, OF ONE-THIRD TO H. O. SWOBODA, INC., OF PITTSBURGH, PENNSYLVANIA, A CORPORATION OF PENNSYLVANIA, AND TWO-THIRDS TO WESTINGHOUSE ELECTRIC & MANUFACTURING COMPANY, A CORPORATION OF PENNSYLVANIA.

IRONING MACHINE.

Application filed February 10, 1919, Serial No. 276,097. Renewed September 26, 1922. Serial No. 590,599.

This invention relates to improvements in ironing machines. The principal object of the invention is to provide an ironing machine that is of very simple construction, 5 of maximum efficiency in operation and that is cheap to manufacture. A further object is to provide a machine of this type in which the cooperating ironing members are moved into and out of engagement by the same 10 power employed to drive the machine thus giving the operator the minimum amount of work in connection with the operation of the machine and allowing him the freedom of his hands at all times as the machine need 15 not be touched by the operator's hands to stop or start it.

With the foregoing and other objects in view the invention consists in the combination and arrangement of parts to be herein- 20 after fully described, pointed out in the appended claims and illustrated in the accompanying drawings which form a part of this specification and in which—

Fig. 1 is a plan view, partly in section, of 25 the machine with the housing removed.

Fig. 2 is an end elevation with the housing partly broken.

Fig. 3 is a fragmentary view of a slightly 30 modified form of the machine.

Fig. 4 is an enlarged fragmentary view, 35 partly in section, of one of the springs and connections employed.

Fig. 5 is an enlarged fragmentary view 40 partly in section.

Fig. 6 is a perspective view of a pinion 45 employed.

Like reference characters denote corre- 50 sponding parts throughout the several views.

The machine comprises the stand formed 55 of the two lateral members 1 connected by the rods 2, said stand carrying the receiving table 3 whereon the frame 4 is carried that is provided with the feed table 5. Se- 60 cured to and carried by the frame 4 is the

stationary shoe 6 of convexo-concave forma- 65 tion and extending longitudinally through the shoe and journaled in bearings 7 thereof is the rotary shaft 8. Loose upon the shaft

50 outside the shoe is a pinion 9 which is re- cessed upon one lateral face to afford clear-

ance for a clutch section 10 which is fast upon the said shaft 8 and which clutch section is adapted for releasable engagement with the clutch section 11 loose upon shaft 55 8 and slidably keyed to a worm gear 12 which encircles said shaft and is loose there- upon. The worm gear 12 is in mesh with the worm 13 of drive shaft 14 which shaft is provided terminally with the pulley and 60 fly wheel 15 which is connected by belt 16 with the pulley 17 of the motor shaft which shaft is driven by the motor 18 carried by the table. A housing or cover plate 20 may be provided for the pulleys 15, 17 and belt 65 16 if desired. Referring again to the pinion 9 the same is formed with two oppositely disposed laterally projecting lugs 21 which are secured to or constantly in engagement with the clutch section 11 so that rotary 70 movement of the same is transmitted continuously to said pinion. The clutch section 11 is formed with an annular rib 22 which is in engagement with a notch formed in the clutch shifter 23, one end 24 of said 75 clutch shifter being in engagement with the longitudinally slotted portion 25 of an end bearing 26 which is adjustably secured to the frame 4 by the screws 27, the opposite end 28 of said clutch shifter being bifur- 80 cated and engaged by a bell-crank-lever 29 fulcrumed to a support 30 secured to the frame 4, said bell-crank-lever being connected by a cord 31 to a link 32 carried by a foot lever 33 fulcrumed to one of the connecting rods 2 of the stand, said cord 31 passing through a plurality of guide eyes 85 34. The clutch shifter is yieldingly retained in such position as to normally keep the clutch sections 10, 11 disengaged by means 90 of the flat spring 23^a secured to the frame and bearing against the shifter. Anchor rings 34^a secured to the cord 31 serve to limit the movement of the same and to prevent sudden jerks being transmitted to the 95 clutch shifter.

The said shaft 8 is provided at its ex- 100 treme ends with the elongated discs 35, 36, each disc being provided at one end with a pin 37 and the disc 35 being provided with the cam-shaped lugs 38 arranged at its ends upon one lateral face, the two lugs 38 being

disposed upon opposite sides of the longitudinal center line of the disc. The frame 4 supports or is formed with elongated bearings 39 wherein the roller shaft 40 is disposed, said shaft being movable laterally in its bearings in a direction toward or away from the shoe 6. Fast upon the said shaft is the roller 41 and also the gear 42 which members, in one position of the shaft in its bearings, are adapted for engagement respectively with the shoe 6 and pinion 9. Loosely secured to the ends of shaft 40 are the threaded eye-bolts 43 which are connected to similar eye-bolts 44, carried by the disc pins 37, by the powerful contractile springs 45, adjusting nuts 46 serving to firmly secure said springs and eye-bolts together, or said springs may be threaded upon the bolts as shown in Fig. 1. In the form of machine shown in Fig. 3 the springs 45 are of the expansion type and the pinion 9 is in mesh, releasably, with the interiorly toothed gear wheel 42. The gearing in the machine here illustrated is disposed toward the front of the machine while the gearing in the preferred form of the device is disposed toward the back of the machine as will be apparent from reference to the drawings.

The operation of the machine follows: The motor, when running, drives the pulley 15, worm shaft 14, worm gear 12, clutch section 11 and pinion 9 continuously, clutch section 11 being keyed to the worm gear 12 and pinion 9 being formed with the lugs 21 engaging the clutch section 11. While the clutch sections 10, 11 are disengaged, however, the shaft 8 remains stationary. To drive the roller shaft and roller to perform, in connection with the shoe, the ironing operation the operator depresses the pedal 33 which meshes the clutch sections 10, 11 through the medium of cord 31, bell crank 29 and clutch shifter 28. Just previous to the act of depressing the pedal the machine is in the position illustrated in Fig. 1 with the roller and shoe, and the pinion 9 and gear wheel 42 disengaged. When the shaft 8 makes one half of one revolution the discs 35, 36 have moved through an arc of 180 degrees and the cam-shaped lug 38 adjacent the disc pin engages the clutch-shifter-end 24 and throws the same outward or in a direction to separate the clutch sections 55 when the shaft 8 will cease instantly to rotate due to the resistance offered by the powerful springs 45 which are then in alignment with the shafts 8, 40 and the crank pins 37, the spring then being at its extreme tension or on dead center. The shoe and roller, as well as the pinion 9 and gear 42 are now in engagement and rotating continuously and will so remain until the operator again depresses the pedal 33 to again mesh the clutch sections. The ironing is done, of

course, by the roller and shoe while they are in engagement, the operator feeding the garments upon the roller in the usual manner. When the operator depresses the pedal 33 while the pinion 9 and gear 42 are in mesh the shaft 8 will rotate one half of one complete revolution when the cam-shaped lug 38 remote from the disc pin 37 will engage the clutch shifter and again disengage the clutch sections thus stopping shaft 8 with the roller 41, shoe 6, and gearing in disengaged relation.

What is claimed is:—

1. In an ironing machine, a frame, a shoe carried by said frame, a normally stationary rotary shaft associated with said frame and shoe, a rotary roller shaft journaled in said frame and adapted for movement laterally in its bearings, a roller arranged upon said shaft for cooperation with said shoe, means normally loose upon said first named shaft for transmitting rotary movement to said roller shaft in a predetermined position of the same in its bearings, foot controlled means whereby said first named means may be made fast to its shaft to cause a predetermined movement of the same, means whereby rotary movement of one of said shafts will cause a movement of the other shaft laterally in its bearings and subsequently arrest the rotary movement of said first named shaft.

2. In an ironing machine, a frame, a shoe carried by said frame, a normally stationary rotary shaft associated with said frame and shoe, a rotary roller shaft journaled in said frame and adapted for movement laterally in its bearings, a roller arranged upon said shaft for cooperation with said shoe, a gear fast upon said roller shaft, gearing loose upon said first named shaft for operative engagement with said gear when said roller shaft is in a predetermined position in its bearings, foot controlled means for making said gearing fast to said first named shaft to cause a predetermined movement of the same, means whereby rotary movement of the first named shaft will cause a movement of said roller shaft laterally in its bearings and a subsequent release of said gearing from said first named shaft.

3. In an ironing machine, a frame, a shoe carried thereby, a normally stationary shaft associated with said frame and shoe, a rotary roller shaft associated with said frame and adapted to move laterally in its bearings, a roller fast upon said roller shaft for cooperation with said shoe, means associated with said first named shaft whereby rotary movement may be imparted to the same and whereby continuous rotary movement is imparted to said roller shaft in one position of the same in its bearings, and means whereby rotary movement of the first named shaft will impart movement to said roller shaft

laterally in its bearings and subsequently arrest the rotary movement of said first named shaft.

4. In an ironing machine, a frame, a shoe carried thereby, a normally stationary rotary shaft associated with said shoe, a rotary roller shaft associated with said frame and adapted for movement laterally in its bearings, a roller fast upon said roller shaft for cooperation with said shoe, a gear fast upon said roller shaft, gears loose upon said first named shaft, a clutch for releasably connecting one of said gears fast to its shaft, another of said gears being adapted for operative engagement with the first named gear in one position of said roller shaft in its bearings, foot controlled clutch-shifting means carried by said frame, said means including a shifter having one bent termination, and means whereby partial rotation of the first shaft will impart movement to said roller shaft laterally in its bearings and, subsequently, cause movement of said shifter through engagement with the bent end of same.

5. In an ironing machine, a frame, a shoe carried thereby, a normally stationary shaft journaled in said shoe, a rotary roller shaft journaled in said frame and adapted for movement laterally in its bearings, a roller fast upon said roller shaft for cooperation with said shoe, a gear fast upon said roller shaft, gears loose upon said first named shaft, a clutch for releasably connecting one of said gears fast to its shaft, another of said gears being adapted for operative engagement with the gear of said roller shaft in one position of the same in its bearings, a clutch shifter, foot controlled means for moving said clutch shifter in one direction, and means whereby partial rotation of said first named shaft will impart movement to said roller shaft laterally in its bearings and subsequently cause return movement of said clutch shifter.

6. In an ironing machine, a frame, a shoe carried thereby, a normally stationary rotary shaft journaled in said shoe, a rotary roller shaft journaled in said frame and adapted for movement laterally in its bearings, a roller fast upon said roller shaft for cooperation with said shoe, a gear fast upon said roller shaft, gears loose upon said first named shaft, a clutch for releasably connecting one of said gears fast to its shaft, another of said gears being adapted for operative engagement with the gear of said roller shaft in one position of the same in its bearings, a clutch shifter, foot controlled means for moving said clutch shifter in one direction, elongated discs fast to the ends of said first named shaft, crank pins carried by said discs, eye-bolts carried by said crank pins and by the said roller shaft, contractile springs connecting said eye-bolts,

and cam-shaped lugs arranged upon one elongated disc upon opposite sides of its longitudinal center line for operative engagement with said clutch shifter whereby said clutch is operated to release said gears and stop rotation of said first named shaft.

7. In an ironing machine, a frame, a shoe carried thereby, a normally stationary rotary shaft journaled in said shoe, a rotary roller shaft journaled in said frame and adapted for movement laterally in its bearings, a roller fast upon said roller shaft for cooperation with said shoe, a gear fast upon said roller shaft, gears connected together and loose upon said first named shaft, a clutch for releasably connecting one of said gears fast to its shaft, another of said gears being adapted for operative engagement with the gear of said roller shaft in one position of the same in its bearings, elongated discs fast to the ends of said first named shaft, connection between said discs and said roller shaft whereby partial rotation of said discs will impart movement to said roller shaft longitudinally of its bearings, cam-shaped lugs arranged upon one face of one of said elongated discs and upon opposite sides of its longitudinal center line, a clutch shifter having one bent end disposed in the plane of movement of said cam-shaped lugs in one position of said shifter, a spring engaging said shifter for yieldingly retaining the same in a predetermined position, and foot controlled means for actuating said clutch shifter to cause movement of the same in one direction.

8. In an ironing machine, a frame, a shoe carried thereby, a normally stationary rotary shaft associated with said frame and shoe, a rotary roller shaft journaled in said frame and adapted for movement laterally in its bearings, a roller fast upon said roller shaft for cooperation with said shoe, a gear fast upon said roller shaft, gearing loose upon said first named shaft, for operative engagement with said gear in one position of said roller shaft in its bearings, means for making said gearing fast to said first named shaft to cause rotary movement of the same, said means including a clutch shifter, discs upon the ends of said first named shaft, pins carried by said discs, flexible connection between said disc pins and the said roller shaft, and means carried by one of said discs for operative engagement with said clutch shifter each time the aforesaid shafts and disc pins are brought into alignment with each other.

In testimony that we claim the foregoing as our own we have hereto affixed our signatures.
